UNITED STATES PATENT OFFICE.

WELLINGTON W. MUIR, OF LOCKPORT, NEW YORK, ASSIGNOR TO GENERAL MOTORS CORPORATION, OF DETROIT, MICHIGAN, A CORPORATION OF DELAWARE.

VACUUM TANK.

Application filed September 6, 1921. Serial No. 498,848.

This invention relates to vacuum tanks which are adapted to utilize engine suction for lifting a liquid from a lower to a higher level.

5 One of the several objects of my invention is the provision of improved means for operating the suction controlling mechanism without the use of springs or spring operated links and levers.

10 Another object of the invention is the provision of improved means for giving a quick and positive action to the operating valves.

With these and other objects in view which will appear as the description proceeds, the invention consists in the novel construction and arrangement of parts herein-after described, particularly pointed out in the appended claims and illustrated in the accompanying drawings, in which:

20 Fig. 1 is a side elevation of portions of an engine showing the invention applied;

Fig. 2 is a vertical section of the vacuum tank;

25 Fig. 3 shows a modified form of tank and outlet or dump valve, parts in section and parts broken away;

Fig. 4 is a vertical section of a modified form of the device;

30 Fig. 5 is a vertical section of a modified form of the device, parts broken away;

Fig. 6 is a vertical section of another modified form of the device;

35 Fig. 7 shows a modified form of the outlet or dump valve arrangement shown in Fig. 6;

Fig. 8 shows a modified form of the device, parts in section, parts broken away;

40 Fig. 9 shows another modified form of the device, parts in section and parts broken away; and

Fig. 10 shows a modified form of the device shown in Fig. 9, parts in section and parts broken away.

45 My device is not limited in its application to any particular use, but for the purpose of description and illustration it is shown as being employed in connection with a fuel feeding system for hydrocarbon motors.

50 On the drawing, the reference numeral 10 designates a carburetor, 11 a mixing chamber 12 the throttle and 13 the intake manifold of a common form of internal combustion engine.

55 A vacuum tank 14 is adapted to be secured by any suitable means, as by the perforated

straps 15 and 16, in an elevated position relative to the carburetor 10. It is preferably located beneath the hood in the usual manner. This tank may be made in any convenient manner as for instance, by superposing one flanged cup-shaped member 17 on a lower flanged cup-shaped member 18 so that the flanges are adjacent to each other. A partition 19 has its outer edge extending between the cup flanges. The partition and flanges are bolted together by bolts 20 as clearly shown in Fig. 2. By this arrangement a tank having an upper pumping or vacuum chamber 21 and a lower or receiving chamber 22 is provided. The lower or receiving chamber 22 is provided with an aperture in its bottom wall in which is engaged a perforated pipe attaching nipple 23 having its outer end screw-threaded. A passage 24 having the turn-cock 25 therein has one end attached to the nipple 23 and its other end to the carburetor 10 for delivering fuel from the receiving chamber to the carburetor, as required.

55 The pressure in the receiving chamber is maintained at that of the atmosphere by means of a passage connecting it with the external air. This passage may be of any suitable form as the tube 26 which has one end secured in the top wall of the cup 17 and its other end in the partition 19.

60 A float chamber having bottom and side walls but no top wall is secured within the vacuum chamber 21 in any suitable manner. The following arrangement for securing the float chamber in position constitutes a convenient manner for assembling the parts. Both the partition and the bottom wall of the float chamber are provided with aligned openings 28. An internally threaded valve 90 guide or housing member 29 is adapted to be secured about the openings 28 by means of the nut 30. The flange 31 of the nut 30 engages beneath the partition and is adapted 95 to draw the bottom of the float chamber into firm engagement with the partition.

65 The nut 30 is provided with an air vent or aperture 32 the upper end of which is formed into a valve seat. The apertured nut 30 constitutes an air inlet passage. A 100 valve 33 carried by the hollow operating rod or guiding tube 34 is adapted to engage the valve seat in the nut 30. The operating rod 34 is adapted to slidably engage in an aperture 35 in the guide or housing member 29 105 110

which fits closely about said rod. The float 36 is secured to the intermediate portion of the operating rod 34.

A suitable guide is provided for the upper end of the operating rod 34. As shown, a valve guide or housing member 37, similar to the guide member 29, is provided. This guide member 37 may also be internally threaded. A flanged screw-threaded pipe nipple member 38 having an aperture 40 therethrough is adapted to engage the guide member 37 to clamp the top wall of the vacuum chamber between the guide 37 and the flange 39 on the member 38 to thereby make an air-tight connection. The apertured member 38 constitutes an air outlet or suction passage. The lower end of the aperture 40 constitutes a valve seat which is adapted to be engaged by the valve 41 rigidly secured to the upper end of the hollow operating rod 34. While the valves 33 and 41 are shown as being attached to the same operating rod and arranged in alinement, it is understood that any suitable arrangement may be had so long as they are both positively operated by the float 36. A pipe 41' adapted to be attached to the nipple member 38 and the intake manifold 13 affords a communicating passage from the intake manifold through the passage 40 and aperture 42 to the vacuum chamber 21.

A pipe or passage 43 (see Fig. 1) is adapted to have one end connected to a reservoir, not shown, and its other end is connected to the vacuum chamber by any suitable means, as by the perforated nipple 44. Attached to the inwardly extending end 45 of the nipple 44 is a tube 46, the lower end of which extends beneath the upper edge 40 of the float chamber in order to prevent the fuel from the main reservoir flowing directly into the float chamber. The lower end of the tube 46 may be provided with a strainer 47 of any suitable form. A liquid outlet passage 48 is provided in the partition 19 for permitting the liquid in the vacuum chamber to pass into the lower chamber 22 when the air is permitted to enter the vacuum chamber. It will be noted that the lower edge of the passage 48 terminates in an annular comparatively sharp edge 48' which is adapted to constitute a valve seat for a valve 49 which may be in the form of a sphere of metal or other suitable material pivotally mounted in the outer end of the lever 50 to freely rotate about the pivot 49'. There is such a comparatively small surface engaged by the valve seat that the likelihood of any foreign substance, deposit or the like, adhering to the valve and tending to unseat the same is reduced to a minimum. Moreover, the convex surface of the valve causes the discharging liquid to be deflected about the valve to thereby keep the surface thereof washed clean. The rotat-

able feature of the valve is also considered an important feature of my invention. The liquid in discharging will cause the valve to rotate more or less and thus continually presenting new surfaces to the valve seat 70 will prevent an accumulation of deposit between the valve and its seat. In other words, the valve is a self-cleaning one. The lever 50 is pivoted to the support 51. The free end 52 of the lever is adapted to act 75 as a counterweight for the valve.

The float chamber 27 is provided adjacent its bottom portion in the side wall thereof with a small aperture 53. The operating rod 34 may be in the form of a hollow rod or 80 tube and has small apertures 54 and 55 adjacent the upper and lower ends respectively whereby air entering the inlet 32 may pass through the aperture 55 into the tube 34 and conducted along the tube and passes 85 out through the aperture 54 above the liquid in the upper chamber to equalize the pressure between the upper and lower chambers of the tank.

Attention is directed to the fact, that 90 the air for equalizing the pressure between the two chambers is drawn into the upper chamber from the lower one and is led directly to the top of the fluid within the upper chamber. This arrangement permits the liquid fuel to flow freely through the dump valve when the same is open, because it will not be necessary for any air to enter through this valve to equalize the pressure between the two chambers. Were the air 100 that enters the passage 32 compelled to bubble up through the liquid in the upper chamber, the resistance would be such that more or less of the air would likely pass upward through the passage 48 and thereby prolong 105 the discharging action besides unnecessarily agitating the liquid.

Attention is also directed to the fact that the fluid for equalizing the pressure between the two chambers is supplied by the lower 110 chamber. It will thus be seen that as the lower chamber fills up the air or vapor in the upper portion of the lower chamber will not be discharged into the air to be lost, but will be drawn into the upper chamber 115 to equalize the pressure and then be drawn into the engine by the exhausting device. This is considered an important feature, because the gasoline vapor which forms in the lower tank as a result of heat due to the proximity of the vacuum tank to the engine will be drawn to a great extent into the upper chamber and from there into the intake manifold instead of being lost by escaping 120 into the air. By this arrangement the passage or tube 26 becomes principally an air intake for the lower section of the tank.

In the operation of the device, starting 125 with the parts in the position shown in Fig. 2, suction operating through the passage 130

40 will exhaust the air in the upper chamber and cause the liquid from the reservoir to flow through the passage 44 into the upper chamber. The liquid will continue to rise 5 in this chamber until it overflows the top of the float chamber. Some of the liquid will have entered the float chamber through the small orifice 53, but this orifice is made so small that the liquid rises much faster on the 10 outside of the valve chamber than it does on the inside. When the liquid overflows the top of the comparatively small float chamber it very quickly, almost instantaneously, raises the float 36. The float being connected to 15 the operating rod 34 operates the valves 41 and 33 to close the suction inlet and to open the air inlet 32. Air immediately enters from the lower chamber through the passage 32, small aperture 55, hollow operating 20 rod 34, and out at 54 above the level of the liquid thus equalizing the pressure between the upper and lower chambers upon which the valve 49 will open and permit the liquid to flow into the lower chamber. The liquid 25 in the float chamber will in the meantime be flowing out through the aperture 53 to lower the float 36 to open the suction passage and close the air inlet, which completes the cycle of operation.

30 The modified form of the device shown in Fig. 3 differs from the form shown in Fig. 2 in that the lower receptacle 22' may be a receptacle of any size and be open or closed. The valve 33 has an extension 54' 35 extending freely down through the inlet passage 32 and through the bifurcated end of the lever 52. A contact member 54^a is secured to the lower end of the extension 54' which is adapted to engage the bifurcated end of the lever 52 when the valve 33 is raised by the float 36. The extension 54' moves freely through the lever 52 in the opposite direction. When the float moves upwardly the contact member 54^a engages the lever 52 and elevates it to unseat the valve 49, thus preventing the possibility of its sticking and preventing a discharge of the liquid into the lower tank.

50 In the modified form of the device shown in Fig. 4 the valve guide or housing 29^a has a tubular extension 55^a which is adapted to extend to a point adjacent the top of the valve chamber. This extension is larger than the valve stem and is adapted to permit 55 the air to pass upwardly between its inner wall and the valve stem. The float 36^a is connected to the valve stem 34^a by means of a bail 56 which engages an elongated aperture 57 in the valve stem 34^a. This elongated opening permits lost motion connection between the float and the stem. The operation is similar to the form shown in Fig. 2.

55 In the modification shown in Fig. 5 the float chamber is secured to a support 58

carried by the partition 19. The support 58 is provided with opposed apertures 59 and 60 adjacent its lower end. A screw threaded plug 61 engaging in the lower end of the support 58 secures the same to the partition 19. The plug 61 is provided with two spaced apertures 61' and 61^a. The valve stem 34^b is arranged similar to the corresponding valve stem 34 in the form shown in Fig. 2 except that its lower end is 70 provided with a piston that is adapted to slide up and down within the support 58. When the piston is in its lowered position it seals the apertures 59 and 60. An aperture 62 through the piston is in communication with the hollow operating rod 34^b. The aperture 62 is between the apertures 61' and 61^a in the clamp 61 and consequently when the piston is at its lowermost position in contact with the plug 61 the apertures 62 75 and those in the plug 61 will likewise be sealed.

When the parts are in the position shown in Fig. 5 air from the lower chamber is free to pass through the aperture in the plug 61, the aperture 62, through the passage in the stem 34^b, and out through the aperture 54^b above the level of the liquid, thus permitting the liquid to flow through the apertures 59, 60, 61' and 61^a into the lower 80 chamber.

85 The modification shown in Fig. 6 differs from the form shown in Fig. 2 in that the valve 49^d is in the form of a disc instead of being spherical in form.

90 The comparatively sharp edge 48' of the passage 48 is adapted to seat on the flat disk 49^d which is carried by the lever 50^d. If desired, the valve may be mounted on a stem 60^d rotatably mounted in the lever 50^d 95 whereby the valve is rotated more or less during the discharge of the liquid from the upper chamber and kept clean thereby.

100 The modified form shown in Fig. 7 differs from that shown in Fig. 3 in that the valve 49^e is shown as being a flat valve instead of a spherical one. This valve differs from the form shown in Fig. 6 in that the valve stem 60^e of the valve 49^e is pivotally mounted in the lever 50^e as shown at 50'. This pivotal movement about a horizontal pivot insures a perfect seating of the valve on the valve seat 48' of the passage 48.

110 In the form shown in Fig. 8 the valve for the suction passage is dispensed with. The float chamber 27^c is made integral with the portion 19^c. The arrangement of the float portion of the valve stem and valve support is substantially the same as that shown in Fig. 4. The upper end of the valve stem 34^c is pivotally connected at its upper end to a lever 63. The lever 63 is pivoted to a support 64 carried by the top of the chamber. The free end of this lever has pivoted thereto a valve 65 which is 115 120 125 130

adapted to close an air passage 66 when the float is lowered but when the float is elevated the lever is adapted to unseat the valve 65 and permit the entrance of air through the passage 66 which in turn will permit the liquid in the vacuum chamber to flow past the valve 49°. It will be noted that in this form the suction is continuous through the restricted passage 40°.

- 10 In the modified form of the device shown in Fig. 9 the arrangement of the air inlet valve is such that the valve 67 is placed on the outside of the tank. This valve has a stem 68 extending down through the passage 69 and is adapted to be pivoted to a lever 70 fulcrumed at 71. The free end of the lever is connected to a rod 72 to which the float 73 is attached. An attaching member 74 having an aperture 75 therethrough 15 is adapted to form a guide for the lower end of the rod 72. A plug 76 is adapted to pass through the partition 19° and engage the support 74 and holds the parts in assembled relation.

- 20 25 It will be noted that in this form of device there is no provision made for permitting the air from the lower chamber to get into the upper chamber. The lower chamber is kept at atmospheric pressure by the air flowing through the passage 26°. When the float 73 is elevated by the incoming liquid the valve 67 is unseated thus equalizing the pressure between the vacuum chamber 21 and the atmosphere which will permit the liquid in the chamber 21 to flow through the passage 48° into the lower chamber 18.

- 30 35 The modified form shown in Fig. 10 differs from that in Fig. 9 in that the equalizing tube 26° is arranged externally of the upper chamber. This tube may extend to any desired height. It may extend high enough to constitute an overflow pipe where necessary or desirable.

- 40 45 It will be noted that in all the forms shown the air inlet for restoring atmospheric pressure to the upper or vacuum chamber is so arranged that the air is conducted to a point above the liquid contained therein. This construction prevents 50 unnecessarily agitating the liquid which would otherwise occur were the inlet air compelled to pass upward through the liquid in restoring the upper chamber to atmospheric pressure. It will also be noted 55 that the aperture 53 in all the forms shown is unobstructed by any valve or closure and that it constitutes the sole outlet for the liquid in the float tank. By making the outlet valveless, there are no valves or closures 60 to stick and cause trouble. This aperture being open at all times insures certainty in the lowering action of the float and consequently a sure and positive movement of the valve or valves operated thereby.

- 65 It will be understood that various changes

may be resorted to in the form, construction, composition and arrangement of the several parts without departing from the spirit and scope of my invention; hence I do not wish to limit myself strictly to the structure herein set forth, but—

What I claim is:

1. In a device of the class described, a vacuum chamber, an exhaust passage connected thereto, a liquid inlet, a liquid outlet, a valve for said outlet, an air inlet and means for controlling the flow of air through said inlet, said means including a float chamber having a single constantly open liquid outlet in the walls thereof functioning independently of said float. 75

2. In a vacuum tank having an air inlet and a valve therefor, the combination of a float and mechanism associated therewith for operating said valve, said mechanism including a float chamber for containing said float, and having a single liquid outlet in the walls thereof, said outlet being always uncovered, substantially as shown and described. 80

3. In a device of the class described, a vacuum chamber having an exhaust passage connected thereto, a liquid inlet, a liquid outlet, a valve for said liquid outlet, an air inlet, a valve therefor, a float for operating said air inlet valve, a float chamber for containing said float, said float chamber being provided with a single valveless liquid outlet, substantially as shown and described. 85

4. In a device of the class described, a vacuum chamber, a section passage connected to said chamber, a valve for said passage, a float chamber, there being a restricted passage connecting said chambers, a float in said float chamber for operating said valve, a receiving chamber, means for discharging liquid from said vacuum chamber to said receiving chamber, and means for conducting air from the receiving chamber to the upper portion of the vacuum chamber when said suction passage is closed. 100

5. In a device of the class described, a vacuum chamber having an air inlet, a valve for said inlet, a float chamber, and a float in said chamber for operating said valve, a single, constantly open passage being provided between said chambers through which liquid may flow to and from said float chamber. 115

6. In a device of the class described, a vacuum chamber having an air inlet and outlet, and a liquid inlet and outlet, a dump valve for said liquid outlet, a hollow rod having apertures adjacent its upper and lower ends, valves for said air inlet and outlet operated by said rod, and means for operating said rod substantially as shown and described. 125

7. In a device of the class described, a

vacuum chamber having an air inlet and outlet, and a liquid inlet and outlet, a valve for said liquid outlet, aligned valves for said air inlet and outlet, an apertured housing for said air inlet valve, a hollow guiding rod for said air inlet and outlet valves engaging said housing and having a laterally extending aperture adjacent each end thereof, one of said apertures being within said housing, a float chamber about said housing having an aperture in one wall thereof and a float within said float chamber for operating said rod, substantially as shown and described.

15 8. In a liquid pumping system, a lower chamber, an upper chamber, a float chamber within said upper chamber, an air passage leading from said lower chamber through said float chamber to the upper 20 part of said upper chamber, a float within said float chamber, and a valve for said air passage arranged to be actuated by said float.

9. In a liquid pumping system, a lower 25 chamber, an upper chamber, a partition between said chambers, a third chamber above said partition, an air passage from said lower chamber through said partition and into said third chamber, said passage opening above the level of liquid in said third chamber, and means responsive to level of liquid in said third chamber for controlling flow of air from said lower chamber through said passage.

30 10. In a liquid supply system, a pumping chamber, a receiving chamber, a receptacle having communication with said pumping chamber adapted to permit overflow into said receptacle when the liquid in the said 35 chamber reaches its highest level, a passage admitting air to the upper part of said receptacle and pumping chamber, a float in said receptacle controlling flow of air through said passage, and constantly 40 open liquid conducting means between the lower portion of said receptacle and said

pumping chamber, said means providing the sole means for flow of liquid into said receptacle during the filling of said pumping chamber until said overflow begins. 50

11. In a liquid supply system, a pumping chamber, a receiving chamber, a partition between said chambers, a float receptacle seated upon said partition, apertures through the partition and the bottom of 55 the receptacle, and means associated with said apertures for securing together the receptacle and partition.

12. In a liquid pumping system, a suction chamber, a receiving chamber, a float chamber in said suction chamber, a float in said last-named chamber, an air passage leading from said receiving chamber to said suction chamber above the level of liquid therein, and a valve carried by said float and controlling passage of air through said inlet. 60

13. In a liquid pumping system, a suction chamber, a receiving chamber, a float chamber in said suction chamber, a float in said float chamber, an air inlet leading 70 from said receiving chamber through said float chamber to the upper part of said suction chamber, an air outlet for said suction chamber, and valves carried by said float for controlling flow through said inlet and outlet. 75

14. The combination of a fluid discharge passage, a valve seat at the discharge end of said passage, a spherical valve adapted to engage said seat, a support upon which 80 said valve is pivotally supported adapted to carry the same toward and from said seat and to permit free rotation about said pivot so as to bring different portions of said sphere into engagement with said seat, 85 said parts arranged to hold said valve, when in the open position, in the path of fluid discharged through said passage to thereby clean the valve.

In testimony whereof I affix my signature. 90

WELLINGTON W. MUIR.
